UNITED STATES PATENT OFFICE.

WILLIAM KOCH, OF NEW YORK, N. Y., ASSIGNOR TO THE KRUSE CHECK AND ADDING MACHINE COMPANY, OF SAME PLACE.

CHECK-PRINTING AND ADDING MACHINE.

SPECIFICATION forming part of Letters Patent No. 367,213, dated July 26, 1887.

Application filed July 13, 1885. Serial No. 171,452. (No model.)

To all whom it may concern:

Be it known that I, WILLIAM KOCH, of the city, county, and State of New York, have invented new and useful Improvements in Check-5 Printing, Numbering, and Adding Machines; and I do hereby declare that the following is a full and exact description thereof, reference being had to the accompanying drawings, and to the letters of reference marked thereon, 10 making a part of this specification.

My invention relates to apparatus for printing and delivering checks of different denominations and registering the sum of the denominations of all checks issued.

15 The object of the invention is to produce a machine which shall not only with positive accuracy print or emboss from a continuous strip of paper a series of checks, each of the precise denomination denoted and determined 20 by the position of an indicator, but also consecutively number the checks as issued and permanently register the sum of the denominations of all checks so issued, and which shall be exact and durable in all its movements; 25 and it consists in the novel construction, combination, and arrangement of mechanism which is hereinafter fully described in detail.

In the accompanying drawings, Figure 1 is 30 the rear elevation of my check-machine with the rear face of the casing removed and with portions of the machine broken away or removed to illustrate underlying parts, the printing-wheels being illustrated as brought together in position for printing the check-35 strip; Fig. 2, a transverse section in the irregular line $\alpha\alpha$ of Fig. 1, looking toward the left, with the cover of the case removed, a detached sectional view of the inner end of the printing-crank in its normal position when at 40 rest being included in the view; Fig. 3, a transverse section in line yy of Fig. 1, looking toward the right, with the cover of the case removed; Fig. 4, a front elevation of the mechanism, the front plate of the casing being 45 removed to expose the same, and the brake for the reel of paper omitted; Fig. 5, a front elevation of the exterior of the machine, a portion of the indicator-lever being broken away to illustrate its spring-actuated stop-bolt; Fig. 6, an end view of a portion of the

gearing by which the adding mechanism is actuated; Fig. 7, a plan view illustrating the sliding cover for the paper-guideway; Fig. 8, a detached elevation of the stop mechanism for the adding device; and Fig. 9, a central vertical section of the machine, looking in same direction as in Fig. 1, illustrating the combination therewith of a consecutive numbering device for numbering each check issued.

The machine is operated by two cranks, one 60 of which, represented by the letter A, (see Figs. 3 and 5,) is mounted upon the journal C of a spur-wheel, C, and vibrates over the face of a semicircular index-plate, A', fitted upon the front face of the case of the machine. 65 Upon this index-plate A' are marked in plain figures the numerals denoting the several denominations for which checks are required. In the drawings these are represented as increasing by five, from 0 to 100. (See Fig. 5.) 70

The index-plate A' is made in the form of an arc having the axis of the crank A as its center, and its lower concave edge is serrated with a series of notches corresponding to the number of the ordinals marked on the index-75 plate, the apices between the notches being made to present each a sharp angle sloping directly to the inner angle of the notch on either side of it, as shown in Fig. 5. The end of the crank-arm is provided with a finger, A², 80 to project and sweep over the ordinals. A bolt, A³, (see Fig. 5,) is fitted in a longitudinal recess upon the under or inner side of the crank-arm, and is combined with a spring which operates to force it out beyond the end 85 of the arm into contact with the serrated edge of the index-plate so as to engage its notches.

The power of the spring is such as that considerable force is needed to move the crank from notch to notch, so that it may not be readily or accidentally displaced, and as the bolt may not rest between the notches, because of the sharp angle forming the apex between each notch, it will operate automatically not only to check and stop the crank at each notch, but 90 will automatically carry the type-wheel actuated by the arm far enough in one direction or the other to bring one of the series of types thereon invariably into line of print before the crank-arm is brought to a stop. This device 95 100

facilitates the ready and accurate adjustment and stoppage of the indicator-finger A² over any desired figure in the scale.

The indicator-crank A and the spur-wheel C rotated thereby serve to actuate a train of gear-wheels, which operate to bring into position a pair of printing-wheels for printing, or embossing between them, upon an interposed strip of paper, numbers corresponding to those on the index-plate A', as hereinafter described.

The second crank, represented by the letter B, (see Figs. 2 and 5,) is fitted upon the end of a shaft, B', whose rotation is made, as herein-after described, to lock the printing or embossing wheels when adjusted, force them together upon the interposed strip of paper, number consecutively the blanks for the checks upon the strip, feed the strip forward after it has been printed, and, finally, sever the printed check from the remainder of the strip. A bolt, B², (see Fig. 2,) is fitted longitudinally in the handle of the crank to project out from its inner end, and is forced out automatically by means of a spring concealed within the handle. The crank B is arrested automatically at each complete revolution thereof by the contact of the end of the bolt B² with a stop pin or lug, B³, projecting from the face of the case. To enable the bolt B² to be retracted to permit it to pass the lug B³, the handle is fitted to play longitudinally upon the longitudinal case B', containing the spring, and which is made integral with or securely fitted to the crank-arm, and is so secured to the bolt by means of a head or washer, B⁵, (see Fig. 5,) on the outer end of the latter as that an outward retraction of the handle will operate to draw the bolt and release it from the lug. This automatic stop, which comes into play at each revolution of the printing-crank, prevents effectually an accidental duplication in the issue of a check or a partial movement of the printing-wheels after a check has been printed and issued until the operator is ready for another positive movement.

The wheels D D', by and between which the checks are printed or embossed, are of equal diameter, and are mounted one above the other in a vertical plane at one end of the case and at a right angle to its face. The peripheries of the two wheels are fitted, respectively, with a series of type and an opposite impression-plate for printing, or with male and female dies for embossing the check-strip, said type or dies being made to represent, at equal distances apart, all the figures marked upon the index-plate A'; and the embossing-dies, where used, are carefully adjusted to interlock accurately as the wheels are rotated. The lower wheel, D, is journaled in fixed bearings between two standards, E E, Figs. 1 and 4, and is geared by means of a beveled contrate-wheel, D², formed upon its face, (see Figs. 1 and 2,) and an intermediate beveled pinion, D³, with the main spur-wheel C, actuated by the indicator-crank A.

The upper impression-wheel, D', is journaled

between two curved arms, E' E', pivoted upon the axis of a pinion-wheel, D⁴, (see Fig. 2,) which is journaled in fixed bearings between the standards E E at a point equidistant from the axes of both printing-wheels D and D', when they are superimposed one upon the other in the same vertical plane. The cogs of the pinion-wheel D⁴ gear into the cogs at the side of each of the wheels D and D', (see Figs. 1 and 2,) so that the movement of the lower wheel, D, is constantly imparted to the upper wheel, D', and the two are made to move in unison. The upper wheel, D', is free to swing out upon its pivoted arms E' E' about the pinion D⁴ and away from the lower impression-wheel, D, to admit of inspection or repair, (see dotted lines in Fig. 2,) and in returning into contact with the wheel D' will fall into proper position thereon without possibility of displacement or of making a false registry. The wheel D' is normally upheld out of contact with the wheel D, so as to leave an open space between them, by means of a spring or a spring-actuated pin, E', (see Fig. 4 and dotted lines, Fig. 3,) in the upper end of the standard or support E of the frame, which rises under the end of one of the arms. By applying pressure vertically to the wheel D' the spring is compressed and the arms E' allowed to drop, so as to bring the periphery of the wheel D' into contact with that of the wheel D, and thereby produce an impression therefrom upon a slip of interposed paper. This pressure is obtained from a cam above by means of a swinging yoke, E², (see Figs. 1 and 2,) whose arms are pivoted to the ends of the journal of the wheel D', projecting through the arms E' E'. The cross-bar E' of the yoke is fitted with a friction-roller, a, whose axis is parallel with the shaft F, mounted immediately over the impression-wheels D D' and in the same horizontal plane as the main shaft B' of the printing-crank B, and which is journaled in lateral brackets F' F'', (see Fig. 2,) projecting from the end of the case or frame of the machine. A cam, a', (see Fig. 2,) upon the shaft F, immediately over the friction-roller a, is brought into contact with said roller to bear thereon and force down the yoke E² and bring the wheel D' into peripheral contact with the wheel D at each revolution of the shaft. The swinging yoke E² is upheld in a vertical position over the axis of the wheel D' and in line with the cam a by means of a sliding stop-plate, G, (see Figs. 1, 2, and 3,) which is made to embrace the shaft F and play freely vertically against the face of the journal-bracket F'' at that end of the shaft, so that its lower end will drop below and in front of the upper end of the yoke, as shown in Fig. 2. By lifting the stop-plate G the yoke is left free to swing outwardly, and serves as a handle by which to swing out the wheel D', as shown by the dotted lines in Fig. 2.

A rotary movement of the printing-wheels D D' and of the indicator-crank A, actuating them, (as well as of the adding mechanism geared thereto,) is positively prevented, ex-

cept at the time when the printing-crank B is at rest against the stop B³, by means of a pin or bolt, H, (see Figs. 1, 3, and 9,) mounted to reciprocate horizontally in suitable bearings 5 through the side of the case and the adjacent standard, E, (see Fig. 1,) and to enter one of a series of apertures, s s s, Figs. 3 and 9, pierced in the side of the lower impression-wheel, D, in a circle concentric with the periphery of the 10 wheel. These apertures correspond in number to the numbers on the face of the wheel.

The inner end of the pin or bolt H is made to taper to a point, and the holes are formed in close contiguity, so that the end of the pin 15 shall inevitably enter one of the holes when moved toward it, and in entering the hole will operate as a wedge to move the wheel into exact register with the bolt, and consequently bring the upper number positively into exact 20 line for print. By this device the possibility of a failure of the dies or type to properly register because of lost motion in the gears is absolutely prevented. This pin H is made to enter the particular hole s which properly 25 falls in register therewith, when any one of the numbers is brought into position for producing an imprint, by means of a lever, H', extending from the pin upward to the plane of the shaft F and in line with the outer end 30 thereof. This lever is bent in its length (see Figs. 2 and 3) to adjust it to the difference between the position of the pin H and of the end of the shaft, and is fitted to a hub, H², near to its lower end, which embraces a pivot-pin, H³, upon which the lever is free to oscillate. Its 35 lower end is pivoted to the center of the pin H, and its upper end is coupled by a link, H⁴, (see Fig. 1,) to a crank, H⁵, upon the end of the shaft F. The length of the crank H⁵ and 40 the position of the pivot H³ of the lever are so adjusted that the pin H is withdrawn from the wheel D for a brief interval by the rotation of the shaft, the position or angle of the crank-arm H⁵ with reference to that of the 45 printing-crank B, by which the shaft F is made to rotate, being likewise so adjusted that this withdrawal and release of the pin H from the wheel will take place at the moment the crank B is arrested against the stop B³.

50 The shaft F is geared to the shaft B' by means of the cog-wheels Y Y, (see Figs. 1 and 9,) of equal diameter, so that the two shafts rotate in unison.

A pair of parallel feed-rollers, I I', (see Fig. 55 2,) are mounted in brackets J J, (see Figs. 1, 2, and 4,) fitted to the sides of the standards E E. The journals of the lower roller, I, (see Fig. 2,) turn in fixed bearings in the brackets at such a height as that the periphery of the 60 roller shall touch a horizontal plane intersecting the point of contact of the two printing-wheels D and D'. The journals of the upper roller, I', turn in boxes b b, (see Fig. 1,) which slide freely in longitudinal slots in the brackets J J, vertically above the lower roller, I, and 65 permit the periphery of the upper roller to rest upon that of the lower roller, the pressure

of the upper roller thereon being increased somewhat by means of springs c, inserted and confined in recesses over the boxes b to bear 70 thereon. (See Fig. 1.) These feed-rollers are geared together by cog-wheels I² I² (see Fig. 2) of equal diameter, and an intermittent movement is imparted thereto to cause them to rotate toward each other, in the direction 75 indicated by the arrows in Fig. 1, by means of a large spur-wheel, I³, meshing with the upper wheel and rotating upon an independent stud, I⁴, secured to the front of the casing or frame of the machine. This wheel I³ is 80 actuated by a pawl, K, (see Fig. 4,) pivoted to the longer arm of a lever, K', which is itself pivoted upon the stud I⁴. The opposite shorter arm of the oscillating pawl-lever K' is coupled by a link, K², to a wrist-pin, K³, upon 85 the face of a wheel, K⁴, secured upon the end of the shaft F, so that the rotation of the shaft shall produce intermittently a to and-fro movement of the pawl.

The arms of the oscillating lever K' are of 90 such a length, the wrist-pin K³ is so located, and the diameter of the spur-wheel I³ so proportioned in respect to the cog-wheels I² I² of the feed-rollers that a proportional revolution of the feed-rollers is produced at each rotation of the shaft F immediately after the cam a' on said shaft is released from the friction-roller a on the yoke E³, to permit the upper impression-wheel, D', to rise. The feed-rollers then remain stationary until the printing-wheels D D' have again been brought into contact. 95

The periphery of the wheel K⁴ is toothed to form a rack for a pawl, K⁵, (see Fig. 1,) pivoted to the casing or frame to engage the same 100 and prevent a reverse movement of the wheel, and consequently of the printing-crank B and its connections.

A guideway, L, (see Figs. 1, 2, and 7,) formed in a metallic plate, slotted to permit the printing-wheels and feed-rollers to engage each other in the plane of its upper surface, is fitted and secured to the frame to extend from outside of the printing-wheel inward and project beyond the feed-rollers. (See Figs. 1, 4, and 9.) The way or recess in the upper face of this plate is of suitable width to receive the strip of paper U, from which the checks are to be cut, and the paper is thereby led horizontally in the plane passing between the printing-wheels D and D' and the feed-rollers I and I'. The way L is provided with two covering-plates, L' L'', which are slotted transversely (see Fig. 7) to allow the printing and the feed rollers to pass through the same, and which 115 are fitted to slide longitudinally into place in grooves formed in the inner sides of the way, so as to admit of ready removal in case the paper strip passing through the way becomes caught therein. 120

A knife, M, is secured to a bar, M², (see Fig. 3,) pivoted at one end to the frame of the machine, to extend transversely across the front end of the guideway L at a right angle 130

thereto and to close upon a suitable bed-plate, as shown in Figs. 3 and 9. The free end of the knife bar is thrown up by a spring, M^5 , (see Fig. 3,) and it is forced down with a positive movement by means of a sliding bar, N , fitted to play vertically in suitable ways, $N' N'$, over the center of the knife, and whose upper end is fitted with a friction-roller, e , to engage a cam, N^2 , (see Fig. 9,) on the shaft B' . In to the lower end of this sliding bar a transverse rod, P , is fitted to project outwardly through the casing. Its outer end is fitted with a thumb-key, P' . (See Fig. 1.) Its inner end is fitted with a disk, P^2 , (see Fig. 3,) having two faces cut at right angles to each other and to radii passing through the center of each, the one (the longer face) being much closer to the center than the other. These faces are made to bear upon the knife-bar, and the rod P , to which they are secured, may be turned by the key P' , so as to bring the one or the other of the faces to bear upon the bar, as may be desired, a further movement of the rod and key being prevented by a stop-pin, d , Fig. 1, engaging offsets upon the edge of the key. The depression of the sliding bar N when acted upon by the cam N^2 will bring the one face or the other of the disk P^2 into contact with the knife-bar. If the face of the disk P^2 which is the longest or nearest its center be toward the knife, the knife will not be carried down far enough to make a cut. If the other shorter face be turned downward, the knife will be carried entirely across the end of the guide-way L , so as to sever the paper strip projecting therefrom. If, when the sliding bar N is up, the disk P^2 be turned so as to change the faces, the angle e between them (see Fig. 3) will operate in the movement as a cam to force down the knife independently of the bar, and the paper strip may thus be cut at any time by simply turning the key P' . By setting the disk P^2 so that its short face shall be down, the paper will be fed through by the movement of the machine without being cut.

While the knife-bar is automatically raised by the action of the spring M^5 , its elevation is positively secured, even should the spring become weakened, by means of a cam, M^4 , (see Figs. 2 and 3,) on the main shaft B' , and a bar, M^3 , which, pivoted at its lower end, is bent at its upper end to overhang the cam M^4 , so as to be struck and lifted thereby before the printing-wheel closes upon the paper. This cam M^4 acts but for a moment, leaving the knife-bar free to be depressed thereafter by a movement of the thumb-key P' .

The adding mechanism of the machine (not shown in the drawings) consists of a series of rotating disks geared together in manner to indicate successively the units, tens, hundreds, &c., to be counted thereby, in manner as is common in adding-machines of well-known constructions. These disks are actuated by the rotation of a single-toothed wheel, Q , Figs. 1, 4, and 6, which alone of the adding mechanism is shown in the drawings. This wheel

Q is mounted in the upper part of the frame or casing of the machine approximately in line with the shaft B' and F , and is geared to a larger wheel, R , which is made to rotate intermittently (more or less) at each revolution of the printing-crank B , by means of a spring-actuated pawl, R' , (see Figs. 1 and 4,) pivoted upon the end of an arm, R^2 , in position to engage the teeth of the wheel R . The arm R^2 projects from the hub or collar of a loose pinion-wheel, R^3 , (see Figs. 1, 4, 6, and 8,) mounted to turn freely upon the pivotal axis of the wheel R . The pinion R^3 is in turn engaged by a toothed segment, R^4 , Figs. 1 and 4, upon one end or arm of a bent lever, R^5 , pivoted centrally upon a stud or pin, i , projecting from the casing or frame between the wheel R and the shaft F , as shown in Figs. 1 and 4. The opposite end or arm of this centrally-pivoted lever R^5 is coupled by a link, R , with the crank-pin K^3 on the face of the wheel K^6 , secured upon the shaft F , as hereinafter described.

Thus the rotation of the shaft F will produce a reciprocating movement of the toothed segment R^4 , whose engagement with the loose pinion R^3 will cause a reciprocating movement thereof, and consequently of the pawl R' , over the periphery of the spur-wheel R . As the pawl moves forward it will engage the spur-wheel R and cause its rotation, and the reciprocating movement of the pawl will thus produce an intermittent movement of said wheel and of the adding mechanism geared thereto. The several gear-wheels Q , R , R^3 and the segment R^4 are so proportioned that the complete movement of the segment produced at each revolution of the shaft F will cause one complete revolution of the adding-wheel Q .

The engagement of the pawl R' with the teeth of the wheel R is controlled, so as to limit the extent of the movement which the complete stroke of the pawl will impart to the wheel, by means of a disk, S , whose extreme diameter coincides with that of the extreme diameter of the toothed wheel R , upon whose axis it is mounted, so as to revolve thereon in contact with its inner face. (See Fig. 6.) The pawl R' is made wide enough to extend over the rim of the disk, and resting thereon it is prevented from dropping into and engaging the teeth of the wheel R . A portion of the rim of the disk S is cut away, however, so as to allow the pawl when it reaches this portion of the rim to drop into the teeth of the wheel R . As the pawl reciprocates back and forth over the rim of the wheel R and of the disk S , the degree of the movement of the wheel by the pawl is restricted to the distance left between the point of the disk at which the pawl will drop between the teeth and the end of the stroke of the pawl. This controlling-disk S is carried upon the face of the wheel S' , (see Figs. 1, 4, and 6,) rotating loosely upon the journal of the wheel R . The wheel S' is geared by a train of toothed wheels, S^2 , S^3 , and S^4 with the shaft of the indicator, and it is so ad-

- justed that when the indicator points to the zero on the scale the widest portion of the disk S will be made to cover the entire movement of the pawl R', so that it cannot actuate the 5 wheel R, and when the indicator points to 100 this wide portion of the disk S will be withdrawn entirely from under the pawl, leaving the pawl free to engage the wheel R at the start and to carry it forward during its entire 10 sweep, producing thereby a complete revolution of the adding-wheel Q. The adjustment of the indicator at the intermediate points will in like manner produce such an intermediate adjustment of the cam-disk S that the rotation of the wheel Q will be exactly proportioned to the position at the time of the indicator between its two extreme points at 0 and 100. To prevent the wheel Q and the adding mechanism from moving too far by reason of 15 its momentum when suddenly turned forward, a tooth or lug, t, is formed upon the end of the arm R², (see Fig. 8,) in position to engage the wheel Q so soon as the arm has completed its forward stroke and is about to swing back. 20 This momentary engagement of the wheel Q by the tooth t serves effectually and positively to stop the movement of the wheel Q the instant the pawl R' has completed its forward movement. 25 The indicating device is completed by fitting a disk, T, upon a horizontal transverse shaft, T', mounted in the upper portion of the case, so that the upper half of said disk shall project up through the top of the case. The periphery of the wheel S', carrying the cam-disk S, is toothed, and the shaft T' is geared thereto by means of a pinion, T², (see Figs. 1 and 4,) so proportioned as that the shaft T' and disk T will make one complete revolution at each 30 complete movement of the indicator from 0 to 100, or vice versa. The opposite faces of the disk T are each marked with ordinals corresponding to those upon the indicator-scale, and the disk is inclosed by a covering-case, V, Fig. 35 5, in which openings V' are left opposite each other, one upon each side, through which the ordinals on the disk may be seen one at a time. (See Figs. 4 and 5.) The disk T is so adjusted with reference to said openings that when the 40 indicator A points to any given number on the indicator-plate the same number will appear at the openings in the case, thereby facilitating the determination and publication of the denomination of the check to be printed, and 45 whose amount is to be added to the sum of checks already issued. 50 The paper U for the checks is supplied to the printing or embossing mechanism in a continuous strip from a reel, U', which is mounted 55 to revolve freely upon a transverse pin, U'', at one side of the case in line with the feed-rolls. The pin is free to be drawn out to facilitate the mounting of the reel of paper thereon. When thus mounted to rotate upon the pin U'' 60 as its axis, the reel may be protected by a skeleton frame, W, forming part of the case of the machine. The pin when inserted is pre- 65 vented from being accidentally withdrawn by means of a latch, y, pivoted upon the outside of the frame W, to engage an annular notch 70 in the end of the pin. The free end of the paper strip U is led from the reel to the feed-rolls, and passing between them is carried forward through the guideway L between the printing-wheels D D' and out 75 under the knife M. A weight, g, (see Fig. 1,) secured upon the end of a flexible arm, h, is mounted within the case of the machine in front of the reel U', so as to drop upon the strip of paper as it is led 80 off from the reel, and by its automatic pressure thereon serve as a brake to prevent a too free or rapid movement thereof. 85 5, Figs. 3 and 9, represent printing or embossing dies secured to each side of the knife M, to move therewith and to imprint, at the moment the separation of the check from the strip is effected, a suitable check-mark upon the adjacent edges both of the severed check and of the strip from which it is cut. 90 To provide for the consecutive numbering of the checks issued from the machine, a consecutive numbering-machine, 20, of any approved construction, is mounted upon the guideway L, (see Fig. 9,) back of the feed-rollers I I', in position to print the strip as it passes 95 forward between said rollers. 100 In the accompanying drawings, Fig. 9, the numbering-machine is illustrated as constructed in the well-known form which operates by the reciprocating movement of a vertical plunger, 13. This plunger carries a frame, 14, in which are pivoted the type-wheels 15. These are actuated by a pawl, 16, made to reciprocate horizontally at each vertical movement of the frame by reason of its attachment to a second frame, 17, dependent from a rod, 18, and whose ends move in inclined slots 19 in the standard 20 of the machine. A reverse movement of the numbering-wheels is prevented by pawls 21, fixed to the movable frame 14, in front of the wheels. The types are inked at each movement of the frame 14 by means of a pad, 22, which is made to sweep under and over the face of the type as the carriage moves 105 up and down. A pad, 23, is let into the face of the guideway L in register with the numbering-wheels to facilitate obtaining an imprint therefrom upon the paper slip. The plunger 13 is made to move up and down to 110 produce an imprint of the numbering-wheels upon the strip each time a check is printed or embossed by the wheels D D', by means of a curved lever, 25, which, pivoted at one end to the shaft B', extends thence over a cam-wheel, 115 24, on the second shaft, F, to engage the upper end of the plunger 13. (See Fig. 9.) The lever 25 is thrown up by the cam 24 at each revolution of the shaft F and is forced down by the pressure thereon of a spring, 26, and its oscillation thus produced operates to cause the required vertical reciprocation of the plunger 120 13 of the numbering-machine. 130 In the operation of my machine, the bolt B²

in the handle B of the printing-crank being against the stop B³, the indicator-lever A is turned to the figure on the index-scale representing the denomination of the check to be issued—as, for example, fifty cents. While the spring governing the lever is not strong enough to prevent a ready movement of the lever, its resiliency operating to throw the bolt A³ into the notches in the rim of the index-plate, (see Fig. 5,) tends to stop the lever in line with the several figures, and thus facilitates a quick arrest of the indicator at the desired figure. The movement of the indicator actuating the train of gear-wheels S⁴, S⁵, S², S¹, and T⁵ sets the disk T so that the figure 50, to which the indicator is set, will appear at the opening in the cover V, and at the same time the printing or embossing wheels D D' are turned back or forth until the appropriate type or die for the figure 50 is brought into register and in line with the strip of paper U. It also turns the controlling-disk S into such a position as that the pawl R' is left free to engage the wheel R during fifty one-hundredths only of the length of its stroke. So soon as the printing or embossing wheels have thus been set by a movement of the indicator the handle B of the printing-crank is drawn out to release its stop-bolt B², and the crank is turned. Its first movement, actuating the crank H⁵ and the locking-lever H' connected thereto, operates to throw the bolt H into one of the bolt-holes in the lower printing-wheel, D, and thus prevents effectually any movement of the printing-wheels until the printing-crank B has made a complete revolution, and consequently locks and prevents any movement whatever of the adding mechanism after the check is printed until it has been delivered from the machine. Immediately following the locking of the printing-wheels D D' and of the adding mechanism operated thereby the cam a' is brought into play to force down the upper printing-wheel upon the lower one, so as to imprint the interposed strip of paper U with the figure 50, to which the wheel was set, and simultaneously the pawl R', moving over the disk S, finally drops at one-half the length of its stroke into contact with the wheel R, so as to carry it forward during the remainder of the stroke, the same being far enough, with the index at 50, to produce a fifty one-hundredth rotation of the master-wheel Q in the adding mechanism. As the upper printing-wheel is closed upon the lower one by the action of the cam a', to produce an imprint of the value of the check thereon, the cam 24 upon the same shaft F is in position to permit the spring 26 to force down the lever 25 of the consecutive numbering-machine, and thereby produce an imprint of the number of the next succeeding check upon the blank strip, in preparation for its being fed forward to receive its denominational imprint. So soon as the printing or embossing wheels D D' are relieved from the action of the cam a', and the upper wheel, D', is lifted by the spring E², the movement of the pawl K, which in the

meantime has been carried back to engage the ratchet-wheel I³, by the rotation of the wrist-pin K³, (see Fig. 4,) will cause a rotation of the feed-wheels I I', so that the paper strip U is fed forward, the imprinted portion carried out beyond the knife M, and a fresh portion, imprinted, as described, with its consecutive number, is drawn in between the printing-wheels, in readiness for an impression therefrom. When each intermittent movement of the paper strip is completed, and as the printing-crank B approaches the completion of its revolution, the cam N² is brought into play to force down the knife-bar M² and sever the printed end of the strip, and at the same time imprint the edges both of the check and of the strip on each side of the line of severance with the safety-prints or guard devices. So soon as the knife-bar M² has made its cut it is lifted by the action of the spring M⁵, assisted positively, if need be, by the momentary engagement of the cam or toe M⁴ with the lifting-bar M². If a check is required for more than one hundred cents—as, for example, for one dollar and fifty cents—the thumb-piece P' is turned so as to bring the longer face of the disk P² toward the knife-bar M² (see Fig. 3) before printing the number 50 in manner as above described, so that the movement of the cam N² will not carry the knife down far enough to cut the strip when said number has been printed thereon. After the printing-crank B has made the one revolution required to print 50 the indicator is set at 100 and the disk P² turned to present its shorter face to the knife-bar, so that upon a second turn of the crank B the figure 100 is printed upon the strip in advance of the 50, and the check is severed with the two figures 100 and 50 thereon. The fraudulent separation of this double check into two separate checks for the purpose of presenting one only is prevented by means of the safety-prints produced on the ends thereof by the dies on the knife-bar, the absence of the imprints upon both ends of a check indicating to the cashier that the check was cut in two otherwise than by the machine.

I am aware that the combination of a spring-actuated bolt with a movable piece formed with angular notches to engage the bolt is not new. My improvement in the means for arresting and defining the movement of the indicating-finger A² in reference to the index-plate A' differs from all other analogous devices in that a serrated edge is formed upon the index-plate to present a series of sharp angular apices between the angular notches, whereby the spring-bolt upon the crank-arm is prevented from resting and remaining stationary between the notches, and is automatically guided into the nearest notch by the pressure of the spring which actuates the bolt, so as to carry automatically the type on the type-wheel invariably into position for print whenever the indicating-arm comes to a rest.

I claim as my invention—

1. The combination, with a printing or embossing wheel rotating in fixed bearings, of a second counterpart wheel superimposed upon the first, with the relief-type on the periphery 5 of the one in register with the counterpart intaglio-type on the periphery of the other, the second wheel being mounted to rotate in bearings in a swinging frame pivoted upon the axis of a pinion gearing into cogs on both 10 wheels, substantially in the manner and for the purpose herein set forth.

2. The combination, with a printing or embossing wheel rotating in fixed bearings and a second counterpart wheel superimposed upon 15 the first and mounted to rotate in a frame which is pivoted upon the axis of a pinion gearing into cogs on both wheels, of a spring actuating the swinging frame to lift the upper wheel from the lower wheel, substantially in 20 the manner and for the purpose herein set forth.

3. The combination, with a printing or embossing wheel rotating in fixed bearings and a second counterpart wheel superimposed upon the first and mounted to rotate in a frame 25 which is pivoted upon the axis of a pinion gearing into cogs on both wheels, of a yoke pivoted upon the journals of the upper wheel to swing into line vertically over the axes of the two wheels, and a cam upon a rotating shaft 30 mounted in position to engage said yoke and bear down the upper wheel at each revolution of the shaft, substantially in the manner and for the purpose herein set forth.

4. The combination, with a printing or embossing wheel revolving in fixed bearings and 35 geared to the shaft or spindle of an index-pointer, by whose movement it is set, and with a second independent shaft actuating by its rotation the mechanism for obtaining an imprint from the wheel upon a strip of paper, of a bolt mounted to engage the printing-wheel, a pivoted lever actuating said bolt, and an eccentric upon said second shaft actuating the lever, whereby the bolt is made to engage 40 the wheel during the major part of the revolution of the second shaft, substantially in the manner and for the purpose herein set forth.

5. The combination, with a printing or embossing wheel rotating in fixed bearings and 50 pierced transversely with a series of contiguous holes forming a circle concentric with its periphery and corresponding in number to the type thereon, and with a second counterpart 55 wheel superimposed upon and geared to the first, with freedom to move radially to and from the same, of a reciprocating tapered-pointed bolt mounted to enter said holes and by the wedging action of its pointed end produce 60 positively an accurate registry of the counterpart impression-surfaces on the two wheels, substantially in the manner and for the purpose herein set forth.

6. The combination, with the knife for severing 65 the checks from the check-strip in a check-printing machine and with a sliding bar interposed between the knife-bar and a cam on

its actuating shaft, of a disk having two adjacent flat faces formed upon its rim or periphery at a right angle to each other and which 70 differ in their radial distance from the axis of the disk, the disk being mounted upon a rotating shaft actuated by a thumb-key and journaled in the lower end of said sliding bar, so that either flat face may be brought to bear 75 upon the knife-bar, substantially in the manner and for the purpose herein set forth.

7. The combination, in a check-machine, of the printing-wheels, the mechanism, substantially as described, for obtaining an imprint 80 from said wheels, the crank-shaft B', actuating said mechanism, the spur-wheel R, geared to the master-wheel of the adding mechanism, the reciprocating pawl R', engaging said spur-wheel R and actuated, substantially as described, by the rotation of the crank-shaft B', the recessed or segmental disk S, governing 85 said pawl to control its engagement with the wheel R, and the indicator-arm A and its shaft C', geared meditately both to said segmental 90 disk S and to the printing-wheels, whereby the movement of the indicator-arm to adjust the printing-wheels will simultaneously adjust the segmental disk, and thereby control the engagement of the pawl with the wheel operating 95 the adding mechanism when said pawl is moved by the rotation of the crank-shaft as it produces an imprint from the printing-wheels under said adjustment.

8. The combination, with the printing-wheel in a check-machine and with the lever by which the wheel is adjusted and its position indicated, of a series of angular projections and intervening angular notches, in number corresponding with the number of operative positions of which the printing-wheel is capable, an angular V-shaped catch or bolt fitted upon the lever and adapted to engage said projections and by a wedging contact with the sloping sides thereof to prevent the 100 wheel from standing at rest between any two of its actuating positions, and a spring bearing upon the catch or bolt to enforce its operative pressure upon the sides of the angular projections, whereby the wheel may not rest 110 until the catch or bolt has reached the bottom of the nearest notch, substantially in the manner and for the purpose herein set forth.

9. The combination, with the shaft B', actuating by its rotation the feed and imprinting mechanism in a check-machine, and with a pawl, K⁵, and ratchet-wheel K³, adapted to prevent its rotation in one direction, of a crank, B, geared to the shaft, a stop or lug, B², upon the face of the casing under the crank, and a 120 spring-actuated bolt, B³, playing longitudinally in the handle of the crank to automatically engage said stop and thereby lock the crank and shaft at each complete turn thereof in the opposite direction, substantially in the 125 manner and for the purpose herein set forth.

10. The combination, in a check-printing machine, with a swinging reciprocating arm, R², actuated by the mechanism, substantially

as herein described, which operates to imprint the check, and with a pawl carried by said arm, and a master-wheel in a train of adding-wheels actuated by said pawl, of a tooth or lug upon 5 said arm fitted to engage and stop said master-wheel at the moment its movement by the reciprocating arm is completed, substantially in the manner and for the purpose herein set forth.

10 11. The combination, in a check-machine, with the shaft F and with the crank-pin K³ upon the wheel K⁴, carried by said shaft, of rocking levers K' and R⁵, actuating, respectively, the feeding-rollers and the adding and 15 registering mechanism of the machine, and connecting-rods K² and K⁶, coupling said levers to the one crank-pin K³, all substantially in the manner and for the purpose herein set forth.

20 12. The combination, with a single crank-shaft in a check-machine, of the type-wheels, the lock-bolt engaging one of said wheels, the

numbering device, the paper-feeding rolls, the reciprocating knife, and intermediate mechanism, substantially as herein described, whereby said locking device, type-wheels, numbering device, paper-feeding rolls, and knife are severally actuated by the crank-shafts to produce, consecutively, during a single revolution of the crank a lock of the type-wheels to prevent 30 their rotation, an imprint from said wheels and numbering device on a strip of paper carried by the rolls, a forward movement of the imprinted paper, a severance of the outer end thereof by the knife, and a release of the lock-bolt, all substantially in the manner and for 35 the purpose herein set forth.

In testimony whereof I have signed my name to this specification in the presence of two subscribing witnesses.

WILLIAM KOCH.
